UNITED STATES PATENT OFFICE

137,363

DESIGN FOR A BOND FOLDER OR THE LIKE

Jean Moses, New York, N. Y.

Application November 30, 1943, Serial No. 111,828

Term of patent 7 years

To all whom it may concern:

Be it known that I, Jean Moses, a citizen of the United States and a resident of the city of New York, in the county of Kings and State of New York, have invented a new, original, and ornamental Design for a Bond Folder or the like, of which the following is a specification, reference being had to the accompanying drawings forming a part thereof.

Fig. 1 is a plan view of the inside of a bond folder or the like showing my new design.

Fig. 2 is a perspective view of the inside of the bond folder or the like in partly folded position.

The outside of the bond folder presents substantially the same appearance as the inside.

I claim:

The ornamental design for a bond folder or the like, substantially as shown and described.

JEAN MOSES.
